CLAIM

The ornamental design for an automatic ball launcher, as shown and described.

DESCRIPTION

FIG. 1 is a top, front, left side perspective view of an automatic ball launcher showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear, right side perspective view thereof.

The broken lines in the figures depict portions of the automatic ball launcher that form no part of the claimed design.
